JOHN HAYS HAMMOND, JR., OF GLOUCESTER, MASSACHUSETTS.

SUCCESSIVELY-OPERATED TONE MODULATORS.

Application filed November 17, 1925. Serial No. 69,569.

This invention relates to musical instrument of the percussive type and to improved means for producing music by percussion.

The invention has reference particularly to musical instruments of the pianoforte type and to improved control of musical sound produced by such instruments and it is an object of the invention to provide improved means for initially controlling the least brilliant tone produced by the instrument and for subsequently controlling the more brilliant tone, thereby producing a smooth crescendo effect throughout the intensity range.

I have discovered that by providing a musical instrument of the percussive type such as the pianoforte, with a sound insulated casing having a metal lining so as to form in combination with the sounding board two separate resonating chambers, and that by providing these chambers with movable reflecting devices arranged so that in one position the chambers are closed effectively to suppress the sound, and so that in other positions the chambers are opened or partially opened, the sound emitted from the different chambers in different directions varies with respect to the brilliance of tone. In the case of an instrument of the grand piano type, such as will be illustrated in the present disclosure, it has been found that the least brilliant tone is emitted from the lower resonating chamber and that a relatively greater brilliance of tone is obtained from the upper resonating chamber, and that by separately controlling the sound emitted from these chambers, a very gradual crescendo and diminuendo can be obtained. It is an object of the present invention to provide means for producing such gradual changes in tone.

I have also discovered that when two groups of reflecting devices are positioned above and below the strings respectively as described, a given amount of opening for emission of sound of the two groups of reflectors results in less tone volume being produced from the lower resonating chamber than from the upper one, the ratio being in the proportion of 6 and 8 approximately, and it is a further object of the invention to provide means for controlling the groups of reflectors successively so as to produce a very delicate shading of tone and so that the operation of controlling the tone volume from minimum to maximum can be greatly

prolonged, thus increasing the varieties of expression imparted to the music.

It has also been found that smooth control of tone volume through relatively small apertures is much more difficult than through large apertures, inasmuch as a large change of tone is produced with small change of opening, and one of the features of the present invention relates to the initial control of the group of reflectors through which the smaller volume of tone is emitted and thus providing a more gradual increment.

Other objects will appear from the following description taken in connection with the accompanying drawings in which:

Figure 1 is a top plan view of so much of a grand piano having features of the invention applied thereto, as is necessary to an understanding of the invention;

Figure 2 is a front elevation partly in section of the piano shown in Figure 1.

Figure 3 is a detailed cross section taken on the line 3—3 of Figure 1.

Figure 4 is a bottom plan view of a portion of the mechanism shown in Figure 2.

Figure 5 is a bottom plan view of a modified form of the invention.

Figure 6 is a fragmentary front elevation of a part of the mechanism shown in Figure 5.

Figure 7 is a top plan view partly in section of the piano shown in Figure 5.

Figure 8 is a fragmentary top plan view of another modified form of the invention.

Figure 9 is a bottom plan view of the piano shown in Figure 8.

Figure 10 is a diagrammatic view of part of the mechanism shown in Figure 9.

Figure 11 shows a modified detail as applied to the mechanism shown in Figures 8 and 9.

Figure 12 is a diagram showing the variation of the volume of sound emitted by the tone modulators shown in Figures 1 and 2.

Figure 13 is a diagram showing the volume of sound emitted by the tone modulators shown in Figures 8 and 9.

Figure 14 is a diagram showing the volume of sound emitted by these tone modulators when the adjusting device shown in Figure 11 is used.

Like reference characters refer to like parts in the several figures of the drawings.

In the following description and claims parts will be identified by specific names for

convenience of expression but they are intended to be as generic as their application to similar parts or equivalent constructions as the art will permit.

5 Referring to Figures 1 to 4 inclusive, of the drawings, the invention is shown as applied to a grand piano including a casing 10. For producing musical sound there is provided within the casing 10 a plurality 10 of tuned strings such as 11, tuned to the notes of the musical scale. It will be understood that there may be provided for each note of the musical scale, one or more of such strings, as may be desired. For example, in the lower part of the scale a single string may be employed for each note; in the upper part of the scale three strings may be employed for each note; and in an intermediate part of the scale two strings may 20 be employed for each note. The strings 11 are mounted in a usual frame 12 in a conventional manner. For vibrating the strings for each of the notes of the scale by percussion there is provided a suitable hammer 25 action such as 13 operatively connected to one key 14 of the manual of the piano. A sounding board 15 is provided within the casing 10. A pedal block 16 is carried at the lower end of two upright bars 17 and 18 depending from the bracket 19 secured to the casing of the piano below the manual. A plurality of pedals shown three in number as at 21, 22 and 23 is positioned on the pedal block 16, the two right hand pedals 22 and 35 23 as seen in Figure 2 being connected to the sustainuto and loud pedal action of the piano in a conventional manner, and having no bearing on the present invention need not be further described.

40 The left hand pedal 21 is operatively connected to a vertical reciprocating rod 24, slidably mounted in the bracket 19, and engages at its upper end one arm of a bell crank lever 25. The bell crank lever 25 is 45 pivotally mounted on a pivot pin 26 secured to the bracket 19 and is engaged by a leaf spring 27 secured to the casing of the piano whereby the pedal 21 and associated parts are normally, but yieldingly maintained in 50 the position illustrated in Figure 2. The opposite arm of the bell crank lever 25 is connected to one end of a link 28, the other end of which is pivotally connected to an arm 29 which is rigidly secured to a vertical 55 rotatable shaft 31. This shaft is mounted in spaced bearings such as 32 and 33, secured respectively to portions of the piano casing 10. There is provided on the shaft 31 a collar 34 rigidly secured thereto for preventing the shaft 31 from longitudinal 60 displacement with respect to its bearings. An arm 35 is affixed to the shaft 31 below the lower wall of the casing 10 and is pivotally connected at its outer end, as clearly 65 shown in Figure 4, to a link 36 which is con-

nected to a reciprocating connecting rod 37. The rod 37 is pivotally connected at spaced points with a plurality of arms 38 each of which is mounted upon one of the tone reflectors forming the lower group, and which 70 will be more fully described hereinafter. The rod 37 is formed of a material which is slightly flexible being sufficiently yielding to permit movement of the parts connected thereto. I have found that a rod formed of 75 a material such as brass approximately three-sixteenth inches in diameter is sufficiently yielding for the purpose.

There is secured to the shaft 31 near the upper wall of the casing 10 an arm 41, relatively longer than the arm 35, the outer end of which is pivotally connected to a connecting link 42. The other end of the link 42 is held between a pair of spaced rollers 43 (see Figure 3), which are mounted in a 80 bracket 44 rigidly secured to a reciprocating connecting rod 45. The rod 45 is formed of a material similar to that of the lower connecting rod 37. Two collars 46 and 47 are 85 adjustedly secured to the rod 42. As clearly 90 shown in Figure 1, one of the collars 46 is so positioned on the rod 42 as to maintain a compression spring 48 in position on the rod 42 between the collar 46 and the bracket 44, there being provided a suitable washer 49 95 against the face of the bracket 44 to serve as an abutment for the spring 48. The reciprocating rod 45 is similar to the lower reciprocating rod 37 and is pivotally connected at spaced points with a plurality of 100 arms 51 each of which is mounted on one of the sound wave reflectors such as 52 forming the upper group of sound wave reflectors.

The casing 10 of the piano is provided with oppositely disposed controllable apertures as at 60, 61. (see Figure 2), and the boundary walls intermediate to these apertures may be constructed to include a layer of substantially sound insulating material. The interior face of the boundary walls of the casing is also provided with a layer 62 of sound reflecting material, such as sheet aluminum. The upper group of reflectors 52 are each pivotally mounted on their longitudinal axes in the upper aperture 60 of the 110 casing serving to control the emission of sound in a general upward direction. Each reflector 52 is preferably in the form of an elongated flat member having beveled edges and pivotally mounted to rotate about its 115 longitudinal axis (see Figure 2). Each reflector is provided on its inner surface with a layer 63 of sound reflecting material which may be of sheet metal having a smooth surface such as sheet aluminum.

In the lower aperture 61 of the casing, there is mounted the lower group of reflectors to control the emission of sound. The construction of the lower group of reflectors corresponds to that of the upper 130

group and includes for each reflector a sound reflecting layer on the inner face, which in this instance is the upper surface. Surrounding each of the apertures the casing includes an upper wall 64 and a lower wall 65 skirting the respective apertures, and having the edge beveled to conform to the edge of the contiguous reflector and having on the inner face a layer of sound reflecting material such as has been described with respect to the remainder of the casing.

There are thus formed two resonating chambers, one designated by the reference character 66 (see Figure 2) and extending between the upper series of reflectors and the sounding board 15, and a second resonating chamber designated 67 extending between the sounding board and the lower series of reflectors.

In the operation of the form of invention shown in Figures 1 to 4 inclusive, when the pedal 21 is depressed by the performer the vertical rod 24 is raised thereby rotating the bell crank lever 25 in a counter clockwise direction as seen in Figure 2, against the tension of the retractile spring 27. This movement is communicated to the link 28 and thereby to the shaft 31 which is rotated in a counter clockwise direction as seen in Figure 4. The two differently characterized arms 35 and 41 secured to the shaft 31 are moved in a similar direction, and this motion is communicated to the link 36 and the rod 42, causing them to be moved towards the right of the Figures 1 and 2. As the arm 41 is relatively longer than the arm 35, the upper tone reflectors 45 controlled by the arm 41 will be closed first. The arrangement is such that when the pedal 21 has been depressed sufficiently to close fully the upper group of reflectors, the lower group will still be partly open. Assuming now that the pedal 21 is further depressed, the rod 42 will slide through the bracket 44 thereby compressing the spring 48 without changing the position of the upper group of reflectors. The pedal 21 may then be still further depressed until the lower reflectors 39 have been fully closed.

When it is desired to reverse the action the pedal 21 is released and the leaf spring 27 retracts the mechanism and the lower group of reflectors 39 are opened, it being noted that the spring 48 expands and maintains the upper reflectors 52 closed, until the collar 47 comes into contact with the bracket 44 after which continued upward movement of the pedal 21 will cause the upper group of reflectors to be opened, the movement continuing until the mechanism has reached its normal position, as shown in Figure 2.

In the modified form of the invention shown in Figures 5, 6 and 7, there is shown a grand piano including a casing 90, and including the sound producing mechanism

and actions described and shown in connection with Figures 1 to 4 inclusive. A plurality of pedals shown three in number as at 91, 92 and 93 is provided, these pedals being rotatably mounted in a pedal block 70 94 suspended below the piano casing by means of bars 95. A fourth pedal 96 is rotatably mounted on a lug 97 secured to the block 94. The rear end of the pedal 96 is operatively connected to the lower end of 75 a vertical reciprocating rod 98, the upper end of which is pivotally connected to one arm of a bell crank lever 100, mounted for rotation on a bracket 101 secured to the casing 90, (see Figure 6). The other arm of the bell crank lever is pivotally connected by means of a link 102 to an arm 103, (see Figure 5). The arm 103 is fastened to a vertical shaft 104. A collar 105 is secured to an intermediate portion of the link 102 and there is secured thereto one end of a spring 106, the other end of which is secured to a fixed portion of the casing 90. There is provided on the shaft 104 an arm 107 near the lower wall of the casing 90, and the free end of the arm 107 is pivotally connected by means of a link 108 to a collar 110 carried by a horizontal connecting rod 111. The rod 111 is pivotally connected at spaced points with a plurality of arms 112, each of which is mounted on one of the sound wave reflectors 113 forming collectively the lower group of sound wave reflectors as hereinbefore described with respect to the embodiment of Figures 1 to 4 100 inclusive.

A second arm 114 is fixed to the upper end of the shaft 104 and it has its outer end pivotally connected by means of a link 115 to a collar 117, (see Figure 7). The collar 117 105 is loosely mounted on a rod 118. Two additional collars 120 and 121 are mounted in fixed position on the rod 118 in such a manner as to serve as abutments for the loose collar 117. A spring 122 is mounted upon the rod 118 between one of the fixed collars 121 and the loose collar 117 so as to hold the loose collar normally against the other of the fixed collars 120. The rod 118 is pivotally connected at spaced points with a plurality of arms 123 each of which is mounted on one of the upper sound wave reflectors 124 forming collectively the upper group of sound wave reflectors similar to those described with respect to Figures 1 to 4 inclusive.

The shaft 104 is also provided with an arm 133 affixed thereto, the free end of which is pivotally connected by means of a rod 134 to a collar 135 loosely mounted on a rod 136. Secured to this rod 136 are two spaced collars 137 and 138 each forming an abutment for the loose collar 135. A spring 140 is mounted on the rod 136 between the loose collar 135 and one of the fixed collars 130

138, and normally maintains the loose collar 135 in contact with the other of the fixed collars 137. The rod 136 is slidably mounted in journal bearings 141 and 142 of conventional construction which are carried by the casing of the instrument. The rod 136 is provided with a slotted member 143 arranged at an angle to the longitudinal movement of the rod 136, the slot of which is engaged by a pin 144 mounted on one end of an extension rod 145 which is slidably mounted in journal bearings 146 and 147 carried by the casing of the instrument. Thus the longitudinal movement of the rod 136 is communicated to the rod 145, the rod 145 being effectively an extension of the rod 136.

For transmitting the longitudinal motion of the rods 136 and 145 there is provided a plurality of links 150, pivotally connected to these rods and to a corresponding plurality of sound wave reflectors 151. The side wall of the casing of the piano is opened by movement of these reflectors 151 to emit sound in a horizontal direction. Each of the reflectors 151 is preferably constructed to conform to the curvature of the casing of the piano as clearly shown in Figure 7 and is pivotally mounted as at 152 to rotate about its longitudinal axis. Each reflector is provided on its inner surface with a layer of sound reflecting material which may be of sheet metal such as sheet aluminum.

In the operation of the form of the invention shown in Figures 5, 6 and 7, the three pedals 91, 92 and 93 are operated by the foot and control the action of the piano in the usual manner. When it is desired to suppress the sound the auxiliary pedal 96 is depressed, thereby raising the rod 98, rotating the bell crank 100, pulling the rod 102 and turning the arm 103 which in turn rotates the shaft 104 in a clockwise direction as seen in Figure 5 and in a counterclockwise direction as seen in Figure 6. This will cause the arm 107 to be rotated, thus moving the link 108 to the right, which in turn will move the rod 111 to the right, thus moving the reflectors 113 into closed position.

The arm 114 will also be rotated, thus moving the link 115 to the right which will cause the rod 118 to be moved to the right, thus closing the reflectors 124. These are so adjusted that they will close before the lower set 113. As soon as the reflectors 124 are closed, the collar 117 will slide along the rod 118 compressing the spring 122 until the lower set 113 has entirely closed.

As the shaft 104 rotates, it will also turn the arm 133, which by means of a link 134 will pull the rod 136 which at the same time will move the rod 145. This will cause the reflectors 151 to be closed, after which the collar 135 will slide along the rod 136, thus

compressing the spring 140 until the lower set of reflectors 113 have been entirely closed.

When the pressure of the foot is gradually removed from the pedal 96, the rod 102 will be moved to the right as seen in Figure 5 under the action of the spring 106 which will cause the shaft 104 to be rotated in the reverse direction from that just described. This will first cause the reflectors 113 to be gradually opened and the collars 117 and 135 will slide along the rods 118 and 136 until they engage the collars 120 and 137 respectively, after which any further motion of the shaft 104 will cause the reflectors 124 and 151 to be gradually opened at the same rate that the reflectors 113 are being opened.

In the modified form of the invention shown in Figures 8, 9 and 10, the system is applied to a grand piano 160 which is provided with the usual key board 161 which controls a standard action for striking the strings such as has been described in connection with Figures 1 to 4. The piano is provided with the usual pedal action 162 and also with an auxiliary pedal 163 which is mounted for rotation in a bracket 164 secured to the side of the regular pedal action block. Connected to the rear of the pedal 163 is a rod 164', the upper end of which engages one end of a bell crank 165 which is pivoted at 166 to a bracket 167 secured to the frame work of the piano. The other end of the bell crank 165 is connected to a link 168 to which is adjustably secured a collar 169. To this collar is attached one end of a spring 171, the other end of which is secured to a bracket 172 which is mounted upon the frame work of the piano. The other end of the link 168 is pivoted to an arm 173 which is rigidly secured to a shaft 174. Rigidly secured to the shaft 174 is an arm 175 to the end of which is pivoted a rod 176 which slides between two rollers 177 which are mounted in a bracket 178 which is rigidly secured to a bar 179. The bar 179 is formed of a material similar to that of the rod 37 of Fig. 2. Secured to the rod 176 are two collars 181 and 182. A washer 183 is slidably mounted upon the rod 176 and is held against the bracket 178 by means of a spring 184. Pivoted to the bar 179 is a plurality of arms 185 which are mounted upon an equal number of reflectors 186 which are mounted for rotation about their longitudinal axes in the frame work of the piano. A bracket 187 is provided against which the bar 179 presses when the reflectors 186 are open.

Rigidly secured to the upper end of the shaft 174 is an arm 190 to which is pivoted a rod 191 which slides between two rollers 192, mounted in a bracket 193 which is secured to a bar 194. The bar 179 is formed of a material similar to that of the rod 37 of Fig. 2. Rigidly secured to the rod 191

are two collars 195 and 196. Slidably mounted upon the rod 191 is a washer 197 which is held against the bracket 193 by means of a spring 198. Pivoted to the rod 194 is a plurality of arms 199 which are mounted upon an equal number of reflectors 200, which are pivoted for rotation about their longitudinal axes in the frame work of the piano.

10 In the operation of the modified form of the invention shown in Figures 8, 9, and 10 when the pedal 163 is depressed the rod 164' will be elevated, thereby rotating the bell crank 165 in a counter-clockwise direction. 15 This causes the link 168 to be moved to the right, thus rotating the arm 173, the shaft 174 and the two arms 175 and 190 in a counter-clockwise direction as seen in Figure 9. This causes the two rods 176 and 191 to be moved to the right. The former merely slides through the bracket 178 until the collar 181 engages this bracket. The latter, however, causes the bracket 193 to be moved to the right through the action of the collar 20 195 on the spring 198. This continues until the upper set of reflectors 200 have entirely closed, after which further motion of the rod 191 only produces a compression of the spring 198. The lower rod 176, however, as 25 it continues to move to the right, after the collar 181 has engaged the bracket 178, will cause the lower set of reflectors 186 to be closed.

When the pressure on the pedal 163 is 30 gradually released, the reverse action will take place under the action of the spring 171, thus causing the rods 176 and 191 to be moved to the left. During the first half of the motion, the lower reflectors will be 35 opened, due to the spring 184 pressing against the bracket 178 until the bar 179 comes up against the bracket 187. During this interval, the upper reflectors 200 will remain closed until the collar 196 engages 40 the bracket 193. During the second half of the motion of these rods, the lower reflectors 186 will remain open and the spring 184 will be compressed while the upper reflectors 200 will be opened, due to the collar 196 45 pressing against the bracket 193 until at the end of the motion, both sets of reflectors are 50 fully open. It will be seen from this description of the operation of the structure shown in Figures 8 to 10, that when the 55 pedal is depressed it will cause first the top set of reflectors to be gradually closed, and after they are entirely closed, the bottom set will be gradually closed. When the pressure on the pedal is gradually released the opposite 60 action takes place and the lower set of reflectors will gradually open to their full extent while the upper set remains closed, after which the upper set is gradually opened.

65 In the modified form shown in Figure 11,

the rod 191 is threaded and is provided with a split nut 201. The bracket 193 is provided with a pointer 202 which indicates on a scale 203 which is mounted on two arms 204 and 205, which are rigidly secured to the rod 191. In this way the point at which the reflectors 200 will close with respect to the motion of the foot pedal and also with respect to the closing of the lower reflectors, can be regulated by adjusting the position 70 of the nut 201. A similar device may be provided on the lower reflecting mechanism so that its opening may be controlled in a 75 similar manner by properly adjusting these nuts.

80 By means of the mechanism shown in the accompanying figures, the volume of sound emitted by the upper and lower set of reflectors can be so controlled as to produce varying effects as shown in Figures 12, 13 85 and 14. It has been found by experiment, that the ratio of sound emitted from the bottom and top of a piano is in the proportion of 6 to 8, that is, the volume of sound emitted from below is three-quarters of that 90 emitted from above.

95 Figure 12 shows diagrammatically the control of the volume of sound emitted from the piano described in connection with Figures 1 and 2. In this figure, the abscissa represents the motion of the foot pedal and the ordinates, the corresponding volume of sound emitted. The line 210 represents the volume of sound emitted by the lower reflectors 39 and the line 211, the volume of sound emitted by the upper reflectors 52. This line reaches its zero intensity at the time the upper reflectors are completely 100 closed and while the lower reflectors are still partly open, as described in connection with Figures 1 and 2. The line 212 shows the 105 total volume of sound emitted by both upper and lower reflectors. It will be seen from the shape of the curve 212 that the tone shading is more sensitive as the volume of sound emitted reaches its lower limits, which is found to produce better effects as this seems to be the most important part of the 110 curve for producing finer tonal nuances. The upper part of the line 212 is steeper 115 where the variation of the volume of sound emitted has less tonal effect.

120 In Figure 13 is indicated the variation of the volume of tone emitted by the piano described in connection with Figures 8 and 9, in which the upper set of reflectors 200 are entirely closed before the lower set of reflectors 186 start to close. In this figure the lines 215 and 216 indicate the way in which the volume of sound emitted by the upper 125 and lower reflectors varies, and the line 217 indicates the way in which the total volume of sound emitted by the piano varies. It will be seen from this figure that the extent over which the sound variation is produced 130

has been greatly lengthened so as to prolong the crescendo or diminuendo produced by the reflectors. In this way a finer gradation of tone shading can be obtained over the entire range, thus allowing the pianist to control more accurately the effects produced by this means.

In Figure 14 is shown the variation in the volume of sound emitted by the piano described in connection with Figures 8 and 9, when the adjusting device shown in Figure 11 is applied to both the upper and lower mechanisms. In this case, the devices are so adjusted that the lower reflectors 186 will start to close when the upper reflectors 200 are half closed, and the upper reflectors 200 will be entirely closed when the lower reflectors 186 are half closed. The rate at which the volume of sound emitted by the upper and lower reflectors varies is indicated by the lines 220 and 221, and the rate at which the total volume of sound emitted by the piano is indicated by the line 222. It will be seen from this curve that the volume of sound emitted drops off slowly at first, then more abruptly, during the middle part of the motion of the pedal, and then more slowly again toward the end. By suitable adjustment, the mechanism shown in Figure 11, other desired variations of tone shading may be obtained.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

What is claimed is

1. A modulating system for a pianoforte, comprising a plurality of resonating chambers, a plurality of sound wave reflectors arranged in groups for variably controlling the volume of sound emitted from the different resonating chambers independently, a tone modulating pedal, means operatively connecting said pedal with one of the groups of reflectors, and means including yielding elements interconnecting said pedal and the remaining groups of reflectors for operating the groups of reflectors in successive order.

2. A modulating system for a pianoforte comprising a tone modulating control device, a plurality of sound wave reflectors arranged in groups for variably controlling the volume of sound emitted from the instrument in different directions respectively, means operatively connecting said device with one of the groups of reflectors, and means including a yielding element operatively interconnecting said device and

the remaining groups of reflectors for operating the reflectors in groups successively.

3. A modulating system for a pianoforte comprising a group of sound wave reflectors for variably controlling the sound emitted from the pianoforte in different directions and arranged in groups, an operating arm for each group of reflectors, a control device for said reflectors, and connecting means including a yielding element operatively interconnected between the control device and said operating arms.

4. A musical instrument including a vibratory sound producing element, a casing therefor having controllable apertures arranged in groups for controlling the emission of sound from said element in different directions, a plurality of centrally pivoted rotatable sound wave reflectors positioned in said apertures for variably closing said apertures and arranged in groups, a connecting rod interconnecting the reflectors of each group, a single device for rotating all of said reflectors, means for directly connecting said device with one of said connecting rods, and means including a yielding element operatively interconnecting said operating device with the remaining ones of said connecting rods.

5. A musical instrument comprising a vibratory source of musical tone, a resonant element adjacent thereto for reflecting and for transmitting sound, a plurality of sound wave reflectors arranged in groups to control the reflected and the transmitted sound respectively, means for operating each group of reflectors independently of the remaining groups, a control pedal, a motion transmitting element connecting said control pedal with the operating means of one group of reflectors, and additional motion transmitting devices, each including a yielding element, interconnecting said pedal with the others of said operating means respectively.

6. A musical instrument including a vibratory sound producing element, a casing therefor having controllable apertures arranged in groups for controlling the emission of sound from said element in different directions, a plurality of centrally pivoted rotatable sound wave reflectors positioned in said apertures, for variably closing said apertures and arranged in groups, a connecting rod interconnecting the reflectors of each group, a single device for rotating all of said reflectors, means for directly connecting said device with one of said connecting rods, means including a yielding element operatively interconnecting said operating device with the remaining ones of said connecting rods, and means for modifying the action of said last named interconnecting means.

7. A musical instrument including a vi-

- bratory sound producing element, a casing therefor having controllable apertures arranged in groups for controlling the emission of sound from said element in different directions, a plurality of centrally pivoted rotatable sound wave reflectors positioned in said apertures, for variably closing said apertures and arranged in groups, a connecting rod interconnecting the reflectors of each group, a single device for rotating all of said reflectors, means for directly connecting said device with one of said connecting rods, means including a yielding element operatively interconnecting said operating device with the remaining ones of said connecting rods, means for modifying the action of said last named interconnecting means, and means for indicating the extent of modification of the action of said means. 10
8. A musical instrument including a vibratory sound producing element, a casing therefor having controllable apertures arranged in groups for controlling the emission of sound from said element in different directions, a plurality of centrally pivoted rotatable sound wave reflectors positioned in said apertures, for variably closing said apertures and arranged in groups, a connecting rod interconnecting the reflectors of each group, a single device for rotating all of said reflectors, a connecting device interposed directly between said device and one of said connecting rods, a connecting device including a yielding element operatively interconnecting said operating pedal with the remaining ones of said connecting rods, and an adjustment nut for varying the action of at least one of said connecting devices. 20
9. A musical instrument comprising a vibrating string, a hammer for vibrating said string by percussion, a sounding board adjacent the string for reflecting and for transmitting sound, a casing therefor, a plurality of sound wave reflectors in the walls of the casing and arranged in groups to control the reflected and the transmitted sound respectively, connecting links interconnecting the reflectors of each group independently of the remaining group, a control pedal, a motion transmitting device connecting said control pedal with the connecting link of one group of reflectors, and an additional motion transmitting device, each including a yielding element, interconnecting said pedal with the others of said connecting links respectively. 30
10. A modulating system for a pianoforte comprising a plurality of resonating chambers, a plurality of sound wave reflectors arranged in groups for variably controlling the volume of sound emitted from the different resonating chambers independently, a tone modulating pedal, and means controlled by said pedal for successively operating the groups of reflectors, in groups. 60
11. A modulating system for a pianoforte comprising a plurality of resonating chambers, a plurality of sound wave reflectors for each of said chambers for variably controlling the volume of sound emitted from the respective chambers independently, a tone modulating pedal, and means controlled by said pedal for operating said groups of reflectors successively. 65
12. In a musical instrument, the combination with a piano of a casing having sound openings, a plurality of normally open centrally pivoted closures for said openings, means controlled entirely at the will of an operator for variably closing said closures to control the intensity of sustained notes emitted, means interconnecting said controlled means, and certain ones of said closures, and means including a lost motion device interconnecting said controlled means and the remainder of said closures. 75
13. A modulating system for a pianoforte comprising a plurality of resonating chambers, a plurality of sound wave reflectors arranged in groups for variably controlling the volume of sound emitted from the different resonating chambers independently, a tone modulating pedal, and means including a compression spring controlled by said pedal for successively operating the groups of reflectors, in groups. 80
14. A modulating system for a pianoforte comprising a plurality of resonating chambers, a plurality of sound wave reflectors for each of said chambers for variably controlling the volume of sound emitted from the respective chambers independently, a tone modulating pedal, and means including a compression spring controlled by said pedal for operating one of said groups of reflectors after the remaining groups. 90
- Signed at New York in the county of New York and State of New York this 16th day of November A. D. 1925.
